UNITED STATES PATENT OFFICE.

FRED OLDRYD, OF CINCINNATI, OHIO.

MECHANISM FOR TRANSMITTING MOTION.

Application filed April 11, 1921. Serial No. 460,362.

My improvements relates particularly to mechanism for transmitting motion by means of pawls and ratchet wheels.

The object of the invention is to produce such a mechanism of great strength and adapted to rapid and prolonged operation, under varying conditions, for the transmission of large power.

In the accompanying drawings,

Fig. 1 is a plan of my improved ratchet mechanism applied to a shaft which is to be rotated, parts being broken away;

Fig. 2 is a side elevation of the same mechanism;

Fig. 3 is an upright section on the line, 3—3, of Fig. 2, looking in the direction of the arrow;

Fig. 4 is a section on the line, 4—4, of Fig. 1, looking in the direction of the arrow;

Fig. 5 is a section on the line, 5—5, of Fig. 1, looking in the direction of the arrow;

Fig. 6 is a detail plan showing the rocking member and pawl in the middle position;

Fig. 7 is an upright section on the line, 7—7, of Fig. 1, looking in the direction of the arrow, the positions of the rocking structure and the cam having been changed;

Fig. 8 is a section on the line, 8—8, of Fig. 7, looking in the direction of the arrow;

Fig. 9 is a detail view showing the blade springs and the plates by which said springs are held, the parts being partially separated.

Referring to said drawings, S is a horizontal shaft resting in suitable bearings, B and B¹.

A ratchet wheel, A, surrounds and is keyed to said shaft and has teeth, A¹, directed for rotation of said wheel and shaft clockwise as viewed in Figs. 4, 5, and 7.

At each side of the ratchet wheel is a rocking member, C, which loosely surrounds the shaft, S. At the rear of said rocking members, as viewed in Fig. 1, a set collar, D, surrounds and is fixed to said shaft, whereby said rocking member is prevented from moving parallel to the shaft, S.

Said rocking members extend above the ratchet wheel and are joined to each other by two horizontal cylindrical shafts, P² and E which have their ends extending into apertures, C¹, extending horizontally through the rocking members. The shaft,

P², is surrounded by a bearing, P¹, formed on the forward end of the pitman P.

The bearing, E¹, of the pawl, E², loosely surrounds the shaft, E, the free end or nose, E³, of the pawl extending forward and downward into engagement with the teeth, A¹, of the ratchet wheel.

A bridge plate, F, extends across the space between the upper ends of the rocking members and has its ends resting upon said members. Cap screws, F¹, extend downward through said bridge plate into the rocking members and fix said plate immovably to said members.

The rocking members and the shafts, P² and E and the bridge plate, F, together constitute a rocking structure whereby the pawl, E², and the forward end of the pitman, P, are carried.

If this mechanism were at all times operated slowly and with the rocking structure extending above the shaft, S, as shown in the drawings, the pawl might satisfactorily and reliably make engagement with the ratchet teeth through the action of gravity;

but, as above indicated, the oscillations of the rocking structure are to be frequent and prolonged, and the power to be transmitted is to be large. Furthermore, the mechanism is to be adapted for operation under variations of position of the shaft, S, and the rocking structure.

For example, the part of the machine to which the structure is to be applied may be so turned as to bring the shaft, S, into various positions out of the horizontal, and even so turned as to effect a complete inversion of that part of the machine, including the rocking structure, so that the pitman and the pawl will be below the shaft, S, the pawl tending to turn away from the ratchet wheel by the action of gravity.

This wide range of variation under which the pawl is to work, and the rapidity of the reciprocation and the large power to be transmitted call for the control of the pawl by an efficient spring mechanism which is adapted to permit the ready outward movement of the nose of the pawl in response to outward pressure by one of the teeth of the ratchet wheel, and which will cause the pawl to promptly turn toward the ratchet wheel as soon as the nose of the pawl has passed a tooth. And said spring mechanism must be durable and reliable for ac-

tion under rapid and prolonged oscillation of the rocking structure.

A group of thin, highly tempered steel blade springs, G, G¹, G² and G³ are used for this purpose. These springs are superposed and approximately parallel to the pawl and have their rear ends resting upon the bridge plate, F. A tension plate, G⁴, rests on the upper of said springs. Cap screws, G⁵ and G⁶, extend through said plate and said springs, the screw, G⁶, being placed forward of the screw, G⁵. The lower or inner spring, G, is so curved as to cause its lower end to bear upon the forward or outer face of the pawl near the nose of the pawl. The next spring, G¹, is located above the spring, G, and is shorter than the latter and is so curved as to cause its forward or free end to bear upon the spring, G. Each succeeding spring is shorter than the next lower spring and is so curved as to cause its forward or free end to bear upon the next lower spring. Thus all of the springs assist each other, the resistance of the several springs being combined. Furthermore, every one of these springs is free to bend along its entire length independently of the bending of the other springs. That is to say, the rear ends of the springs are held immovably between the tension plate and the bridge plate, and the forward ends of the springs so bear upon each other as to move in unison excepting for a creeping of the forward end of each spring upon the next lower spring; but between their ends, all the springs are free to bend or flex independently of each other, so that one may bend at one part more than another bends at the corresponding part. This results in slow degrees of movement of the springs relatively to each other. It is obvious that such movement would be absent if only a single larger spring were used or if the forward ends of the springs were so held as to compel movement in unison.

The tension plate, G⁴, already mentioned, rests upon said group of springs and is loosely penetrated by the cap screws, G⁵ and G⁶, said screws extending through relatively large apertures, G⁷, in the plate. Said plate extends forward of said cap screws to approximately the middle of the length of the springs, and said plate is curved downward to conform approximately to the upper face of the upper spring.

By raising or lowering the cap screws, the springs are made to bear downward upon the pawl with corresponding variation of intensity. The openings, G⁷, in the tension plate are preferably made larger than the diameter of the cap screws, in order that either cap screw may be set lower or higher than the other, whereby the tension plate may be tilted so as to bring its outer or free end higher or lower than is the case when its opposite end is parallel to the bridge plate.

The adjustment of the tension plate may be further varied by the use of any desired number of washers, G⁸, on the cap screws, G⁶ and G⁵.

In considering the service to be performed by the spring, it must be noted that during the rapid operation of the mechanism, the sudden stopping of the quick forward stroke tends to throw the free end of the pawl forward away from the ratchet wheel, the pawl being now in the upright position, as shown in Fig. 7. Such tendency to outward movement of the pawl must be definitely overcome, and yet the slipping of the nose of the pawl over the ratchet teeth must be made as easy as is possible.

Preventing failure to engage the ratchet teeth by the pawl on account of forward momentum acting on the pawl at the termination of the forward stroke is especially important in view of the adjusting means herein described for, at the will of the operator, postponing engagement by the pawl with the ratchet teeth until nearly the limit of the forward stroke, at which time the pawl is approximately in the upright position or with its length approximately perpendicular to the bodily movement of the pawl, whereby the momentum acting on the pawl will tend to turn the pawl away from the ratchet wheel.

The means for varying the engagement of the pawl during the stroke, the stroke being of uniform range, will now be described.

On the pawl, near the nose of the latter is a pin or arm, H, which is parallel to the shaft, S, and is long enough to extend into the plane of the cam, H¹, which loosely surrounds the shaft, S, and extends outward from the shaft, S, farther than the position of the arm, H, from said axis when the pawl is in engagement with the ratchet wheel. The outer edge of the cam is concentric to said axis and is of sufficient length to support the arm, H, during any desired part of the stroke. The cam is adapted to be so turned as to be entirely out of the path of the arm, H, or so as to extend into as much of said path as may be desired.

Between the cam, H¹, and the adjacent bearing, B, a spacing sleeve, H², surrounds the shaft, S, and fills the space between said bearing and the cam, whereby the latter is held against movement away from the adjacent rocking member.

On the outer side face of the cam, H, is a wrist, H³, to which is coupled the forward end of a pitman, H⁴. The rear end of said pitman is coupled to a crank, H⁵, which is rigid on a shaft, H⁶, which rests in a stationary bearing, H⁷, in the wall, W. Said shaft extends through said bearing and supports a hand crank, H⁸. A plate, H⁹, is secured by bolts, H¹⁰, to the outer face of the wall, W, concentric to the shaft, H⁶, and

between the crank, H^8 , and said wall. In said plate are sockets, H^{11} , adapted to receive a locking pin, H^{12} , slidably mounted in the crank, H^8 , and controlled by a small rocking lever, H^{13} , adjacent the handle of the crank, H^8 . By depressing said lever, H^{13} , the pin, H^{12} , is drawn away from the plate, H^9 , and out of the socket, H^{11} , in which the pin may at the time be engaged.

10 An expanding spring H^{14} , normally presses the lever, H^{13} , away from the crank, whereby the pin is driven in to any one of the sockets, H^{11} , with which the pin is made to register by the movement of the crank, H^8 . The sockets, H^{11} , are spaced to permit setting the crank, H^8 , in such positions as will cause the placing of the cam, H^1 , into various desired positions. Lugs, H^{15} , formed on the plate, H^9 , limit the throw of the hand crank.

Thus we have a pawl and ratchet transmission mechanism comprising a rocking member which may be actuated continuously at high speed for the transmission of great power through the shaft, S , and the mechanism comprising provision for varying the range of turning of the shaft during every stroke and the complete suspension of transmission being effected by holding the pawl away from the ratchet wheel during the entire reciprocation of the pawl.

I claim as my invention:

1. In a mechanism of the nature described, the combination of a rocking structure, a ratchet wheel, a pawl hinged on said rocking structure in position to bear upon the periphery of the ratchet wheel, and a group of blade springs curved on different radii and superposed and having one end secured to the rocking structure and having the other end arranged to transmit yielding pressure on the pawl, substantially as described.

2. In a mechanism of the nature described, the combination of a rocking structure, a ratchet wheel, a pawl hinged to said rocking structure in position to bear upon the periphery of the ratchet wheel, a tension plate, adjustable means for securing the tension plate, and a group of blade springs superposed and engaged by the tension plate and arranged to transmit yielding pressure on the pawl, substantially as described.

3. In a mechanism of the nature described, the combination of a rocking structure, a ratchet wheel, a pawl hinged to said rocking structure in position to bear upon the periphery of the ratchet wheel, a tension plate, adjustable means for securing the tension plate, and a group of blade springs curved on different radii and superposed and engaged by the tension plate and arranged to transmit yielding pressure on the pawl, substantially as described.

4. In a mechanism of the nature described,

the combination of a rocking structure comprising a bridge plate, a ratchet wheel, a pawl hinged on said rocking structure in position to bear upon the periphery of the ratchet wheel, and a group of blade springs superposed and secured to the bridge plate and arranged to transmit yielding pressure on the pawl, substantially as described.

5. In a mechanism of the nature described, the combination of a rocking structure comprising a bridge plate, a ratchet wheel, a pawl hinged on said rocking structure in position to bear upon the periphery of the ratchet wheel, and a group of blade springs superposed and curved on different radii and secured to the bridge plate and arranged to transmit yielding pressure on the pawl, substantially as described.

6. In a mechanism of the nature described, the combination of a rocking structure comprising a bridge plate, a ratchet wheel, a pawl hinged on said rocking structure in position to bear upon the periphery of the ratchet wheel, a tension plate, and a group of blade springs superposed and engaged by the tension plate and arranged to transmit yielding pressure on the pawl, substantially as described.

7. In a mechanism of the nature described, the combination of a rocking structure comprising a bridge plate, a ratchet wheel, a pawl hinged on said rocking structure in position to bear upon the periphery of the ratchet wheel, a tension plate, and a group of blade springs superposed and curved on different radii and engaged by the tension plate and arranged to transmit yielding pressure on the pawl, substantially as described.

8. In a mechanism of the nature described, the combination of a rocking structure comprising a bridge plate, a ratchet wheel, a pawl hinged on said rocking structure in position to bear upon the periphery of the ratchet wheel, a tension plate having relatively large apertures, binding members extending through said apertures, and a group of blade springs superposed and engaged by said tension plate and arranged to transmit yielding pressure on the pawl, substantially as described.

9. In a mechanism of the nature described, the combination of a rocking structure comprising a bridge plate, a ratchet wheel, a pawl hinged on said rocking structure in position to bear upon the periphery of the ratchet wheel, a tension plate having relatively large apertures, binding members extending through said apertures, and a group of blade springs superposed and curved on different radii and engaged by said tension plate and arranged to transmit yielding pressure on the pawl, substantially as described.

10. In a mechanism of the kind described, the combination of a rocking structure com-

prising two side members and a bridge plate, a ratchet wheel located between the side members, a pawl hinged on said rocking structure in position to bear upon the periphery of the ratchet wheel, and a group of blades superposed and having one end secured to the rocking structure and having

the other end arranged to transmit yielding pressure on the pawl, substantially as described.

In testimony whereof I have signed my name, this 6th day of April, in the year one thousand nine hundred and twenty-one.

FRED OLDRÖYD.
